7 Claims. (Cl. 208—320)

The present invention relates to a novel process for solvent extraction of aromatics and/or other unsaturated hydrocarbons from mineral oil fractions by use of liquid sulfur dioxide as the selective solvent for such hydrocarbons whereby such hydrocarbons are selectively dissolved by said solvent to provide an extract phase rich in aromatic and/or unsaturated hydrocarbons and a raffinate rich in saturated hydrocarbons. More particularly, the invention relates to a plural-stage process for such solvent extraction of mineral oil fractions, and particularly non-lubricating mineral oil fractions, with minimized loss of saturated hydrocarbons to the extract phase while obtaining a raffinate phase of relatively low aromatic content. Still more particularly, the present invention relates to such a solvent extraction process for effective removal, from non-lubricating mineral oil compositions such as kerosene stocks that have been subjected to naphthene dehydrogenation, of the aromatic hydrocarbons present in such naphthene dehydrogenated kerosene whereby to produce in high yields from such naphthene dehydrogenated materials a highly paraffinic fraction useful as an exceptionally high quality fuel for operation of jet engines.

It is well known to those skilled in the art that liquid sulfur dioxide is a selective solvent for aromatic and unsaturated hydrocarbons in mixture with saturated hydrocarbons and various methods have been proposed and utilized to effect extraction of aromatic and unsaturated hydrocarbons from such mixtures with such a selective solvent. Thus, for example, conventional processes have involved the use of a liquid phase process wherein liquid sulfur dioxide is countercurrently contacted with the mineral oil fraction containing aromatic and/or unsaturated hydrocarbons and, more specifically, by feeding liquid sulfur dioxide into the top and the feed stock into the bottom of a suitable tower whereby countercurrent contact is effected to produce a raffinate phase discharged from the top of the tower and an extract from the bottom. The raffinate phase, rich in saturated hydrocarbons with some dissolved SO₂, is then normally treated for removal of SO₂ which is then recompressed and recycled to the tower; and the extract, rich in aromatics and/or unsaturated hydrocarbons and SO₂, is also treated for recovery of SO₂ which is also used for recycle to the tower.

Typical of such conventional operations is the use of pressure sufficient to maintain the SO₂ in liquid phase, temperatures on the order of from about 0 to about +15° F. and use of liquid SO₂ in from about 50 to about 250, and most usually 60 to 150 vol. percent based on the volume of mineral oil fraction to be solvent extracted. Furthermore, in the use of a plural stage process, wherein the raffinate from the first stage from SO₂ extraction is subjected to a second stage extraction with such a solvent, the same or similar conditions of operation are generally used, and mainly with respect to temperatures. In general, such processes are carried out to produce a raffinate of substantially reduced aromatic and/or unsaturated hydrocarbon concentration, base on the feed stock, without regard to the yield of the saturated hydrocarbons and this is particularly so when it is desired to provide a raffinate substantially devoid of or containing not more than about 10% of aromatic hydrocarbons. As is apparent from the description of this invention as is set forth hereinafter, a novel process has

2

been provided whereby in simplified manner a mineral oil fraction containing saturated hydrocarbons in mixture with aromatic and/or unsaturated hydrocarbons can be solvent extracted with liquid SO₂ to provide a raffinate phase, substantially devoid of or containing not more than about 3 volume percent of aromatic hydrocarbons, in a substantially high yield based on the content of saturated hydrocarbons of the feed stock to the process.

In accordance with this invention, a mineral oil fraction containing saturated hydrocarbons and aromatic and/or other unsaturated hydrocarbons is subjected to a first stage extraction with liquid SO₂ and the raffinate from the first stage extraction is subjected to a similar extraction with liquid SO₂ but at a substantially higher temperature than the first stage. As to the first stage, the temperature that is employed is restricted to that above the pour or freeze point of the charge stock to be solvent extracted and, in particular preferred embodiments, the present invention is practiced with charge stocks that have a pour point below -10° F. whereby the first stage is carried out at a temperature above the pour point of the charge stock but not in excess of about +10° F. Where appropriate, the first stage is carried out at as low a temperature as is practical commensurate with the pour point of the charge stock. As to the proportional amount of liquid SO₂ to the charge for the first stage operation, a large amount (volume percent) of liquid SO₂ is used, based on the volume of the feed stock, and in general, from about 150 to about 300 volume percent of liquid SO₂ based on the volume of the feed stock. The raffinate from the first stage is then subjected to a similar extraction step with respect to proportional amount of liquid SO₂ to raffinate but at a substantially higher temperature than the first stage and, in general, a temperature of at least 15° F., and preferably at least 20° F., higher than used for the first stage. Normally, the SO₂ present in the raffinate from the first stage is removed prior to the second stage extraction but such removal of SO₂ is not essential. By use of such a plural stage process at such a temperature differential between the two stages, it has been found that the selectivity of the extraction by liquid SO₂ is markedly increased whereby highly effective extraction of aromatics and/or other unsaturated hydrocarbons is provided with retention to an unexpected extent of the desired saturated hydrocarbons to the extract phase is minimized in the two step process.

For the process embodied herein to provide a combination of high raffinate yields with low aromatic content, there may be used any of many mineral oil feed stocks containing saturated hydrocarbons and aromatic and/or other unsaturated hydrocarbons and from which it is desired to extract the aromatic and/or the other unsaturated hydrocarbons with the saturated hydrocarbons being the more valuable product, or vice versa. Thus, the process may be used for mineral oil fractions such as appropriate mineral oil distillates to produce high cetane number diesel fuels, highly aromatic specialty solvents, highly paraffinic specialty solvents, or any hydrocarbon material wherein a high concentration of either aromatic and/or unsaturates or saturates is desired. In particular, the process embodied herein is particularly adapted to treatment of appropriate mineral oil distillates for preparation of fuels for jet engines and, more particularly, to fractions in the boiling range of kerosenes to remove aromatics and/or other unsaturated hydrocarbons therefrom to produce exceptionally high quality jet fuels in unexpectedly high yields from an SO₂ extraction process. In illustrative embodiments, the process embodied herein is practiced with virgin kerosene

fractions boiling in the range of from about 350 to about 550° F. and containing the following hydrocarbons: paraffins, naphthenes and aromatic hydrocarbons; narrow kerosene cuts boiling in the range of from about 375 to about 525° F. and containing a mixture of such hydrocarbons; and for preparation of jet fuels of exceptionally high quality, kerosene fractions boiling in the aforesaid ranges that have been subjected to naphthalene dehydrogenation to convert all or a substantial amount of the naphthenes to aromatics whereby to produce, as the feed stock for the process embodied herein, a dehydrogenated kerosene fraction composed substantially of paraffins and aromatics and, depending on the extent to which the naphthalene dehydrogenation was effected, a minor amount of naphthenes. Generally, such dehydrogenated kerosenes contain a small amount of olefinic hydrocarbons but, when present, in amounts that normally do not exceed about 3.0%.

In further reference to virgin kerosenes useful as feed stocks for the process embodied herein, such kerosenes can be derived from a variety of crude sources including Mid-Continent, Barco, West Texas, and Middle East (Kuwait) and which kerosenes may contain paraffins, naphthenes and aromatics in the following amounts, in weight percent; from about 30 to about 70 paraffins, from about 20 to about 50 naphthenes, and from about 5 to about 30 aromatics. Specific embodiments include straight run kerosene fractions of the following composition:

	Mid-Continent		ASTM boiling range (375-500° F.)			
			Barco		W. Texas	
	Wt.	Vol.	Wt.	Vol.	Wt.	Vol.
Paraffins	39.9	42.7	42.4	45.1	58.6	61.1
Naphthenes	43.1	42.1	43.8	42.0	33.2	31.8
Aromatics	17.0	15.2	14.3	12.9	8.2	7.1

In reference to use, for the feed stocks to the process embodied herein, of such kerosenes that have been subjected to naphthalene dehydrogenation to convert a substantial amount of the naphthenes to aromatics, the following are compositions of such naphthalene dehydrogenated kerosenes (375-515° F. fractions) derived from the aforesaid specifically defined virgin kerosenes:

	Naphthalene dehydrogenated kerosene		
	Mid-Continent, vol. percent	Barco vol. percent	W. Texas, vol. percent
Paraffins	41.7	44.3	61.7
Naphthenes	4.3	4.0	3.0
Olefins	2.4	1.9	1.4
Aromatics	51.6	49.8	33.9
	100.0	100.0	100.0

In general, however, and with respect to naphthalene dehydrogenated kerosenes, the process embodied herein is carried out with such kerosenes boiling in the range of from about 350 to about 570° F., of the following composition:

	Vol. percent
Paraffins	From about 35 to about 70.
Naphthenes	From about 1 to about 20.
Aromatics	From about 25 to about 60.

In order to further describe the invention, the following embodiments are set forth for purposes of illustration and not limitation. For the embodiments set forth, including for purposes of comparison the results ob-

tained from an SO₂ extraction carried out in conventional manner, the process was carried out in liquid phase in a contacting tower of conventional design in which the liquid SO₂ was fed to the top portion of the tower and the mineral oil fraction to the bottom portion of the tower with obtainment of a raffinate withdrawn from the top of the tower and an extract phase from the bottom.

Example 1

10 Charge to SO₂ extraction: Dehydrogenated West Texas kerosene of the following composition boiling in the range of 407 to 538° F.—

	Vol. percent
15 Paraffins	62.2
Naphthenes	5.1
Olefins	2.8
Aromatics	29.9

20	SO ₂ -unit operating conditions	Conventional one pass operation	Two pass operation of present invention	
			First Pass	Second Pass
25	Charge rate (barrel/day of dehydrogenated kerosene)	3,000	3,100	3,500
	Vol. percent of SO ₂ feed	240	250	200
	Temperature, ° F.	+44	0	+42
30	Yields, per pass:			
	Raffinate, vol. percent	51	65	94
	Extract, vol. percent	49	35	6
	Yields, overall:			
	Raffinate, vol. percent	1.51		2.61
	Extract, vol. percent	1.49		2.39

35	Two Pass Operation of Present Invention					
	First Pass			Second Pass		
	Feed	Raffinate	Extract	Feed	Raffinate	Extract
40	Gravity, ° API	42.7	52.1	27.6	52.1	52.5
	Aniline pt., ° F.	135.3	181.0	10.4	181.0	184.7
	Aromatics content, percent vol.	31.2	2.7	84.0	2.7	1.2
						46.3
						135.5

45 ¹ Properties of feed, raffinate and extract from the conventional one stage operation:

50	Material			Feed	Raffinate	Extract
	Gravity, ° API			43.1	52.9	32.6
		Aniline pt., ° F.	Aromatic content, vol. percent	134.4	184.1	58.5
	29.9			1.7		59.4

² Loss of raffinate to extract in two pass operation:

Bls./1,000 bls. of feed	86
Percent of total potential	12.3
Process efficiency, vol. percent of total potential raffinate that was actually recovered	87.7

55 Note.—Loss of desired raffinate components to extract: 189 barrels per 1000 barrels of feed, or 27.0 percent of the total potentially available raffinate components, i.e., the process efficiency in terms of the total desired raffinate components present in the original dehydrogenated kerosene that was actually recovered as final product was 73.0 percent.

60 It is apparent from the data in Example 1 that the raffinate from the two pass process embodied herein was obtained in a 61 volume percent yield whereas that from the conventional one step operation was 51%, i.e., as compared to the process embodied herein, about 27% of the potential desired raffinate components were lost to the extract in the conventional operation while only 12% were lost to the extract in the process of this invention. As is further apparent from the data in Example 1, the raffinate obtained in the markedly higher yield from the two pass operation was of exceptionally high quality in that the aromatic content was 1.2% (vol.) thereby providing in such high yield a highly paraffinic fraction useful as an exceptionally high quality jet fuel.

Example 2

The following data illustrates the marked improvement obtained by practice of the two stage process, embodied herein utilizing a relatively lower temperature for the first stage than the second stage as compared to results typical of those obtained from a conventional operation using two stages but at the same temperature.

Feed stock: Dehydrogenated Gach Saran kerosene of the following composition boiling in the range of 400 to 534° F.—

Gravity, ° API ----- 39.4
Aniline pt., ° F. ----- 130
Aromatics content, vol. percent ----- 38.9

5

tional method of operation, by treating kerosenes of substantially different concentration of aromatics:

	Dehydrogenated West Texas kerosene	Dehydrogenated Gach Saran kerosene
Aromatic content	29.9	38.9
Yield increases, present process over conventional process, percent -----	19	47

10

Although the present invention has been described with preferred embodiments, it is to be understood that modifications and variations may be resorted to, without departing from the spirit and scope of this invention, as

	Process of the present invention						Conventional operation					
	First pass			Second pass			First pass			Second pass

Process efficiency, vol. percent of total potential recovered (desired raffinate components)				86.1						52.6		

In practice of this invention, it should be apparent to those skilled in the art that the process embodied herein can be carried out with use of more than two stages for extraction with SO₂ as long as there is employed two stages of extraction using successively a relatively low and a relatively higher extraction temperature. However, for most purposes, and as is evidenced by the foregoing description of the invention, a two stage extraction is satisfactory.

Moreover, in practice of this invention, it may be desirable for certain applications to carry out the process embodied herein by subjecting an appropriate feed stock to a first stage extraction with liquid SO₂ at a relatively low temperature to provide a first raffinate and an extract and charging only a portion of the first raffinate to a second stage extraction at a higher temperature than the first stage. For such a process, and for example, the operating conditions for the second extraction may be correlated to produce a raffinate of exceptionally low aromatic content (e.g., not more than about 1 to 2% vol.) and which raffinate can be blended with the remaining portion of the raffinate from the first extraction to produce a blended raffinate product to meet the aromatic content depending on specifications for particular jet fuels.

An important aspect of the discovery on which the present invention is based is that, generally speaking, the advantage in yield of desired raffinate components increases as the aromatic content of the charge stock to the process is increased. In illustration, the following is typical of the increase in yield that is obtained by practice of this invention, as compared to results from a conven-

45 those skilled in the art will readily understand. Such variations and modifications are considered to be within the purview and scope of the appended claims.

What is claimed is:

1. A two stage liquid phase selective solvent extraction process for separating liquid hydrocarbon mixtures of saturated hydrocarbons and unsaturated hydrocarbons into a raffinate phase rich in saturated hydrocarbons and an extract phase rich in unsaturated hydrocarbons with minimized loss of saturated hydrocarbons to the extract phase which comprises subjecting a liquid hydrocarbon mixture, having a pour point below -10° F. and boiling in the range of from about 350 to about 570° F., of saturated hydrocarbons and unsaturated hydrocarbons to a first contact with liquid sulfur dioxide at a temperature above the pour point of said mixture but not in excess of about 10° F. to produce a first raffinate rich in saturated hydrocarbons and a first extract rich in unsaturated hydrocarbons, and subjecting said first raffinate to a second contact with liquid sulfur dioxide at a temperature of at least about 15° F. higher than the temperature of said first contact to produce a second raffinate substantially richer in saturated hydrocarbons than said first raffinate.

2. A process, as defined in claim 1, wherein the liquid hydrocarbon mixture is a non-lubricating mineral oil fraction.

3. A process, as defined in claim 1, wherein the liquid hydrocarbon mixture is a kerosene fraction.

4. A process, as defined in claim 1, wherein the liquid hydrocarbon mixture is a naphthalene dehydrogenated kerosene fraction containing, in volume percent, from about

75

35 to about 70 paraffins, from about one to about 20 naphthenes, and from about 25 to about 60 aromatics.

5. A process, as defined in claim 1, wherein said contacts with the liquid sulfur dioxide are carried out with an amount of from about 150 to about 300 volume percent of sulfur dioxide based on the volume of the liquid hydrocarbon subjected to contact with the sulfur dioxide.

6. A two stage liquid phase extraction process for separating liquid hydrocarbon mineral oil mixtures boiling in the range of from about 350 to about 570° F., having a pour point below -10° F., and containing, in volume percent, from about 35 to about 70 paraffins, from about 1 to about 20 naphthenes and from about 25 to about 60 aromatics into a (1) raffinate phase rich in saturated hydrocarbons and containing not more than about 3 volume percent aromatics and (2) an extract phase rich in unsaturated hydrocarbons with minimized loss of saturated hydrocarbon components of said liquid mixture to said extract phase which comprises subjecting said liquid hydrocarbon mixture to a first contact with liquid SO₂ at a temperature above the pour point of said liquid hydrocarbon mixture but not in excess of about 10° F. to produce a first raffinate rich in saturated hydrocarbons and a first extract rich in unsaturated hydrocarbons, and subjecting

the first raffinate to a second contact with liquid SO₂ at a temperature of at least about 15° F. higher than the temperature of said first contact to produce a second raffinate rich in saturated hydrocarbons and containing not more than about 3 volume percent unsaturated hydrocarbons.

7. A process, as defined in claim 6, wherein the said contacts with the liquid SO₂ are carried out with an amount of liquid SO₂ of from about 150 to about 300 volume percent based on the volume of liquid hydrocarbons subjected to contact with the liquid SO₂.
